UNITED STATES PATENT OFFICE

CHARLES G. KIME, OF CRESTLINE, OHIO, ASSIGNOR TO THE BURCH CORPORATION, OF CRESTLINE, OHIO, A CORPORATION OF OHIO

MEANS FOR SPREADING ROAD MATERIAL

Application filed May 19, 1930, Serial No. 453,727. Renewed March 7, 1932.

This invention relates to that type of spreaders in which a hopper is mounted to run upon a road surface at the rear of a dumping body truck and to be drawn along by the truck and receive from the truck body broken stone or other road material which will be spread over the road surface as it discharges from the hopper. The present invention relates particularly to the rear gate or cutoff of the hopper and has for its object the provision of means whereby the road material may be spread to an even surface or permitted to accumulate to a greater height at the center and gradually taper toward the sides so as to provide a crown for the road. The invention provides a supplemental blade which is independently adjustable upon the rear gate and includes means whereby bending or warping of the supplemental blade under stress will be effectually resisted. The invention is illustrated in the accompanying drawings and will be hereinafter fully described, the novel features being particularly defined in the appended claims.

25 In the annexed drawings:

Figure 1 is a side elevation of the rear end portion of a dumping truck and my improved spreader connected therewith.

30 Fig. 2 is a rear elevation of the spreader, and

Fig. 3 is an enlarged detail vertical section through the rear gate and the supplemental blade mounted thereon.

In the particular arrangement illustrated 35 in Fig 1, the reference numeral 1 indicates a portion of the dumping body of a truck and 2 indicates a portion of the rear end of the chassis upon which the body is hingedly mounted, the body being equipped with an 40 end gate 3 which may swing outwardly to permit discharge of material when the body is swung to a dumping position, as shown. Hangers 4 are secured to the sills of the chassis adjacent the rear end thereof and a cross 45 bar 5 is secured to and extends between the lower ends of these hangers, the hangers being reinforced by braces 6 extending forwardly therefrom to the sills. The hopper or body 7 of the spreader has a downwardly 50 and rearwardly inclined front wall upon the

front side of which are reinforcing bars to some of which are pivoted the rear ends of draft bars 10 which extend forwardly and have their front ends formed into hooks 11 with beveled forward lower edges whereby, if the truck be backed toward the hopper, the draft bars will be caused to ride over the cross bar 5 and drop into engagement therewith. Pivotaly hung above the draft bars 10 are suspension rods 13 which pass through the draft bars and are equipped with wing nuts 14 below the bars adapted to bear against the under sides thereof and thereby support the bars against dropping. Springs 15 are arranged around the suspension rods 13 above the draft bars so that, while the draft bars may yield to ride over the cross bar 5, they will be held to and in engagement with said bar when the apparatus is in use. To effect release of the draft bars, a rock shaft 16 is mounted in the braces 6 and is equipped with a depending crank arm 17 having its lower end disposed to engage below the draft hooks, as at 18. A similar crank arm 19 rises from the rock shaft and is pivoted to an operating 75 rod 20 which extends forwardly to a point near the operator's seat where it may be equipped with a lever or other manipulating device. If the crank 17 be swung upwardly and rearwardly, the hooks 11 will be lifted from the cross bar 5 so that the truck may then be driven forward away from the hopper.

The hopper is supported by rollers 21 upon a shaft 22 which is journaled in bearings 23, the bearings being in turn bolted to blocks 24 which are secured to some of the reinforcements upon the front wall of the hopper. The blocks 24 may be of any form which will accommodate a plurality of openings through the lower front wall of the same to receive 90 fastening bolts whereby the bearings may be secured at a relatively higher or lower point of the hopper so that the bottom of the hopper will be disposed at a greater or less height above the ground surface and the depth of 95 the spread may be thereby approximately regulated. Shoes 28 are also connected with the front wall of the hopper to run upon the ground in paths following the outer sides of the truck wheels while the rollers 21 are in- 100

tended to run in paths at the inner sides of the truck wheels 29, thereby tending to obliterate any ruts which might be formed in the sub-grade of the road by the truck wheels 5 and to contribute to an even deposit of the road material.

The hopper shown in the accompanying drawings is intended more particularly for spreading broken stone and the end or side walls of the hopper are so formed as to terminate in their rear portions at an appreciable distance above the bottom of the hopper. Slidably mounted upon the end or side walls of the hopper are end gates 80 which, when 10 set in their lowest position, will prevent lateral spread of the material as it passes from the hopper but by setting these end gates at higher points the material may be permitted to spread laterally at the same time that it 15 passes to the rear so that the formation of shoulders or of wide spread will be facilitated. Upon the outer side of the end gate 80 adjacent the upper end thereof is a loop or bracket 81 through which passes a hanger 20 82 rigidly secured upon the frame of the hopper at the top of the same so that it constitutes a guide for the end gate in the vertical adjustment of the latter, it being understood that the side edges of the end gate 25 80 are engaged behind cleats or flanges 83 on the hopper so that the end gate will be effectually held to the hopper. A set bolt 84 is mounted in the loop or bracket 81 and is adapted to be turned home against the hanger 82 so as 30 to secure the end gate in its set position.

The rear gate or cut-off 85 is of substantial construction and is provided at its edges with vertical racks or notched bars 86 which are arranged to mate with notched bars or racks 40 87 rigidly secured upon the rear wall of the hopper at the ends of the same. The racks 87 have laterally projecting flanges 88 and upon the ends of the gate are secured arms 89 which project forward past the racks 87 and the 45 flanges 88 adjacent the ends of the hopper, braces 90 being secured to and extending between the said arms and the gate, as clearly shown in Fig. 1. Mounted upon the arms 89 are cams or eccentric levers 91' which are 50 adapted to bind against the front sides of the respective flanges 88 and thereby firmly clamp the racks 86 and 87 in engagement so that the gate will be held in its set position and will ride over the top of the discharging road 55 material so as to reduce the same to a desired level even surface. By swinging the locking lever 91' upwardly, the gate may be raised to the desired height and by then turning the lever downwardly the gate will be 60 firmly secured.

Secured upon the rear side of the gate 85 along the lower edge of the same is an angle bar 91 having openings formed through its rearwardly projecting web at intervals. Secured to this angle bar 91, which serves as a

reinforcement for the lower edge portion of the gate 85, at intervals alternating with the mentioned openings are braces 92 depending from the horizontal web of the bar 91 and imparting additional strength and rigidity 70 to the bar. Disposed between the front vertical web of the angle bar 91 and the front edges of the brackets 92 is a supplemental blade 93 which is adapted to depend below the gate 85 and serve as a cut-off to produce a level upper surface on the road material. The blade 93 has rigidly secured thereto posts or hangers 94 which extend upwardly therefrom through the openings in the horizontal web of the angle bar 91 so that they serve 75 as guides for the blade in its vertical movements. The brackets 92 also serve as guides for the blade and in addition reinforce the blade so as to resist any tendency of the same to buckle or warp under the strain imposed thereon by the load of road material over 80 which it works. The posts 94 also serve as braces for the blade and by their movement through the openings in the bar 91 serve to prevent swaying of the blade as it is adjusted vertically. Some of the posts or hangers 94 adjacent the respective ends of the blade are made somewhat wider than the other posts and have links 95 pivoted to their upper ends, 85 the upper ends of said links being pivoted to the free ends of the lower arms 96 of angle levers which are fulcrumed upon the gate 85 at the upper edge of the same and extend upwardly, as shown at 97, said levers being 90 equipped with latches 98 cooperating with holding racks 99 secured rigidly upon the gate 95 85 so that the levers may be held in a set position. It should be noted, particularly upon reference to Fig. 2, that the lower arms 96 of the levers extend in opposite directions or 100 toward each other so that the levers are oscillated in opposite directions. Each lever is equipped at its upper extremity with a bail or small loop 100 which is adapted to be engaged over the upper free end of the handle 105 of the cooperating latch and thereby hold the latch out of engagement with the rack. There is also provided a coupling bar 101 having a notch 102 in its lower edge near each end, 110 these notches being adapted to be engaged over studs or lugs 103 on the respective levers, one lever, that shown at the left in Fig. 2, having the stud above its fulcrum and the other lever, that shown at the right in Fig. 2, being extended below the fulcrum 115 and having the stud at the lower end of the extension. It will be understood that, if the loop 100 upon one lever be engaged over the adjacent latch handle, the latch on said lever 120 will be held out of engagement with the cooperating rack 99 and both levers may then be adjusted by manipulating the other lever, the movement of the active lever being transmitted to the inactive lever through the coupling bar 101 in an obvious manner. It will 125

thus be seen that the blade 93 may be adjusted from either side of the hopper and it will also be noted that if the coupling bar be removed the levers may be independently adjusted so that either end of the blade may be set higher than the opposite end thereof and the blade thus adjusted to permit a greater deposit of material under one end than under the other end so that a crown may be formed upon the road.

By the use of this supplemental adjustable blade, a very accurate deposit of road material may be attained, the gate 85 being set to permit the load to be deposited approximately to the desired depth and the blade being independently adjusted so as to effect a finer closer adjustment. The guide brackets and posts or hangers cooperating with the blade serve to hold it to a true rectilinear vertical path when it is being adjusted so that there will be no binding of the same against the gate and the openings through which the guide posts or hangers pass are of such dimensions that they will effectually guide the gate but at the same time permit it to be canted within limits by the independent operation of the levers in order to produce the desired crown upon the road. The device is exceedingly simple and efficient and will not add perceptibly to the draft of the apparatus.

Having thus described the invention, I claim:

1. The combination with a hopper to be drawn over a road at the rear of a dumping vehicle and receive road material from said vehicle, of a back gate mounted upon the rear wall of the hopper and vertically adjustable thereon, a supplemental blade carried directly by the gate, and means mounted on the gate above the blade for vertically adjusting the blade.

2. In apparatus of the type described for spreading road material, the combination of a hopper, a back gate vertically adjustable upon the rear wall of the hopper, a supplemental blade carried by the gate, means for vertically adjusting the blade, and guiding elements engaging with the blade to maintain it in a vertical plane parallel with the plane of the gate and resist buckling of the blade.

3. In an apparatus of the type described for spreading road material, the combination of a hopper, a back gate adjustable vertically upon the rear wall of the hopper, a supplemental blade mounted upon the gate, and levers mounted upon the gate adjacent the ends thereof and connected with the blade whereby to set the same for forming a crown in the spread road material.

4. In apparatus of the type described for spreading road material, the combination with a hopper, of a back gate mounted upon the rear wall of the hopper, a guiding web projecting rearwardly from the gate adjacent the lower edge thereof, guiding brackets

depending from said web, a supplemental blade disposed between the gate and said brackets, posts secured to the blade and extending upwardly therefrom through said web, and means connected with the blade for vertically adjusting the same and maintaining it in a set position.

5. In an apparatus of the type described for spreading road material, the combination of a hopper, a back gate on the rear wall of the hopper, a blade carried by the gate adapted to project below the same, levers mounted on the gate above the blade and having arms extending toward each other, links connecting the respective arms with the blade, and a coupling bar engaged with and extending between the levers, one end of said bar being disposed above the fulcrum of the lever to which it is connected and the opposite end of the bar being disposed below the fulcrum of the lever to which it is connected.

6. In an apparatus of the type described for spreading road material, the combination of a hopper, a back gate mounted on the rear wall of the hopper, a supplemental blade carried by the gate, levers mounted on the gate and operable in opposite directions, links connecting the respective levers with the blade, latches carried by the levers, means on each lever for rendering the cooperating latch inactive, and a coupling bar extending between the levers and detachably engaged with one lever above its fulcrum and detachably engaged with the other lever below its fulcrum.

In testimony whereof I affix my signature.
